US00D779513S

(12) **United States Design Patent** (10) Patent No.: **US D779,513 S**
Murillo et al. (45) Date of Patent: ** Feb. 21, 2017

(54) **DISPLAY SCREEN WITH GRAPHICAL USER INTERFACE**

(71) Applicant: **Microsoft Corporation**, Redmond, WA (US)

(72) Inventors: **Oscar E. Murillo**, Redmond, WA (US); **Kristoffer S. Schultz**, Redmond, WA (US); **Cheryl Nicole Platz**, Redmond, WA (US); **Addison K. Linville**, Seattle, WA (US); **Kelly Rose McArthur**, Seattle, WA (US); **David A. Walker**, Bellevue, WA (US); **Tyrone Samson**, Seattle, WA (US); **Vikram Bapat**, Kirkland, WA (US); **John Henson**, Seattle, WA (US); **Jason Ryan Farmer**, Snohomish, WA (US); **Craig Fox**, Bellevue, WA (US); **Stefanie Lyn Tomko**, Bellevue, WA (US); **Lisa Stifelman**, Palo Alto, CA (US); **Shane Jeremy Landry**, Woodinville, WA (US)

(73) Assignee: **Microsoft Corporation**, Redmond, WA (US)

(**) Term: **14 Years**

(21) Appl. No.: **29/495,942**

(22) Filed: **Jul. 7, 2014**

(51) LOC (10) Cl. **14-04**

(52) U.S. Cl.

USPC **D14/486**

(58) **Field of Classification Search**

USPC **D14/485-495**

CPC **G06F 3/048; G06F 3/0482**

See application file for complete search history.

Primary Examiner — Kevin Rudzinski

(74) Attorney, Agent, or Firm — Banner & Witcoff, Ltd.

(57) **CLAIM**

The ornamental design for a display screen with graphical user interface, as shown and described.

DESCRIPTION

The patent or application file contains at least one drawing executed in color. Copies of this patent or patent application publication with color drawing(s) will be provided by the Office upon request and payment of the necessary fee.

The FIGURE is a front view of a display screen with graphical user interface showing our new design.

The broken line showing of the remainder of the user interface and the remainder of the display screen is for environmental purposes only and forms no part of the claimed design.

1 Claim, 1 Drawing Sheet

(1 of 1 Drawing Sheet(s) Filed in Color)
